UNITED STATES PATENT OFFICE.

AUGUST S. HELD, OF FREEPORT, ILLINOIS, ASSIGNOR TO STOVER MANUFACTURING COMPANY, OF FREEPORT, ILLINOIS, A CORPORATION OF ILLINOIS.

SPRING-HINGE.

SPECIFICATION forming part of Letters Patent No. 694,273, dated February 25, 1902.

Application filed January 19, 1901. Serial No. 43,842. (No model.)

To all whom it may concern:

Be it known that I, AUGUST S. HELD, a citizen of the United States of America, residing at Freeport, in the county of Stephenson and State of Illinois, have invented certain new and useful Improvements in Spring-Hinges, of which the following is a specification.

My invention relates to spring-hinges of the class ordinarily used for screen-doors and the like; and the general objects are to increase strength, lessen cost, obtain perfect action, and to provide for removing the door from the casing without removing any member from the part to which it is ordinarily attached and without the use of any tools.

In the drawings, Figure 1 shows the hinge in elevation as it appears when upon a door. Figs. 2, 3, 4 are sections on the lines 2 2, 3 3, 4 4, respectively, the latter view, however, showing the hinge opened one hundred and eighty degrees. Fig. 5 is a face view of a modified construction, parts being broken away. Fig. 6 is a section on the line 6 6, Fig. 5. Fig. 7 is a face view similar to Fig. 5, showing a second modification. Fig. 8 is a section on the line 8 8, Fig. 7. Fig. 9 is a view similar to Fig. 1, showing a third modification. Figs. 10, 11 are sections on the line 10 10, Fig. 9, showing the hinge in its closed and open positions, respectively.

All the forms involve the well-known idea of having force exerted by a spring in a line at one side of the pintle-line, thereby tending to open or close the door, according as the same is opened beyond or not beyond a certain dead-point or point where the line of force in moving from one side to the other of the pintle-line intersects the pintle-axis of the hinge. It also involves advantages over other hinges in that it has novel features which give a stronger and smoother-working hinge at a less cost and which afford a more convenient means for throwing the spring out of action and at the same time allowing the complete disengagement of the leaves from each other.

In Figs. 1, 2, 3, 4, A represents a hinge-leaf provided with four suitably-spaced parallel ears, forming, in effect, an end pair $a a'$, a central pair $a' a''$, and an opposite end pair $a'' a'''$, the ears of the first pair and last pair

being connected by preferably integral pintles $a^4 a^5$ in the same line and the ears of the second pair being connected by a pivot-bar a^6 not in the same line as the pintles just mentioned. Upon this pivot bar or rod is mounted a roller C to serve as a bearing for a certain spring. B represents a second leaf provided with two hook-like ears $b b'$, adapted to fit between the ears $a a'$ and $a'' a'''$, respectively, and to engage the corresponding pintles $a^4 a^5$. D is a C-shaped spring having one end perforated and passed through a slot b^3 to engage a lug b^3 upon the leaf B, whereby it is secured against undesired movement, and having its other end normally pressing outward against the roller C. The spring by its action and reaction tends to force the leaf A outward and the leaf B inward, and thereby the hooked ears are held constantly in engagement with their pintles. Thus fitting each ear of one leaf closely between two rigid ears of the opposite leaf prevents relative movement, gives great strength with little material, prevents the exertion of leverage upon the pintles, and at the same time gives the hinge the appearance of having a nearly-continuous central cylinder of metal, a feature found important in the market. As the hinge opens the spring's point of contact with the roller, while always at a fixed distance from the roller's axis, is first gradually forced away from the pintle-axis, owing to the eccentric mounting of the roller, and thereby the tension of the spring increases; but on further opening the point of contact approaches the pintle-axis, lessening the tension. Thus the spring tends first to close the door and later to open it and hold it open. It is to be observed that while the spring is pressed away from the pintle to a greater or less degree it presents different portions to the bearing, but without slipping, and hence without the use of unsightly and dust-retaining oil creaking is entirely avoided. The form of the spring may be greatly varied, and in Figs. 5, 6 I have shown it as a wire doubled to form a loop, which rests upon the roller e and has its two branches oppositely wound to form coils E, the wire ends engaging the leaf B. Figs. 7, 8 show a similar construction, with the end of the loop cut off, 100

the coils F F' and the portions f f' being unconnected and the roller being preferably grooved to aid in keeping the portions f f' in place.

5 Figs. 9, 10, 11 illustrate a hinge like that shown in Fig. 1, except that the ears a a³ of that form are omitted, and a bridge b⁴ spans the space in which the free end of the spring D swings back and forth as the hinge opens to and closes. This bridge lies entirely without the outer limit reached by the spring in ordinary use, and the space between it and the spring increases as the spring is compressed in the movement of the door. If, then, when 15 the space is near a maximum, any not-readily-crushed body, as X, Fig. 11, be inserted in the space, the spring is thereby kept compressed, and when in the further movement of the door in the usual way the roller has 20 moved away from the spring the leaves A B may be readily separated, or, in other words, the door may be removed. If the door be again replaced, it is only necessary to open it to a maximum, thereby compressing the spring 25 and allowing the inserted body to fall out, for all parts will then be in place and operative, as at the outset.

What I claim is—

1. The combination with a hinge-leaf provided with a bearing at one side of the pintle-axis, of a second leaf pivotally connected with

the first, and a spring secured to the second leaf and normally pressing said bearing in a line of direction passing to one side of the pintle-line, said second leaf being provided 35 with a member passing over the pressing portion of the spring and lying without the path followed by the latter as the hinge opens and closes; whereby the spring being pressed away from said member by the opening of the 40 hinge may be held out of action by inserting between it and said member a body not readily crushed.

2. In a spring-hinge, the combination with a hinge-leaf provided with two widely-separated ears, of a second leaf provided with two ears connected by a rod at one side of the pintle-axis and adapted to fit between the ears of the first leaf and form therewith two pairs of pintle-connected contiguous ears, a 45 roller mounted upon said rod, and a spring mounted upon the first leaf and normally pressing said roller in a line of direction passing to one side of the pintle-axis.

In witness whereof I have hereunto set my 55 hand, at Freeport, in the county of Stephenson and State of Illinois, this 31st day of December, A. D. 1900.

AUGUST S. HELD.
